CLAIM

We claim the ornamental design for cable boot and connector, as shown and described.

DESCRIPTION

FIG. 1 is a side isometric view of a cable boot and connector in accordance with the new design;

FIG. 2 is a side elevation view of the cable boot and connector of FIG. 1;

FIG. 3 is a bottom plan view of the cable boot and connector of FIG. 1;

FIG. 4 is a top plan view of the cable boot and connector of FIG. 1;

FIG. 5 is a rear elevation view of the cable boot and connector of FIG. 1; and,

FIG. 6 is a front elevation view of the cable boot and connector of FIG. 1.

The broken lines throughout the drawing figures are included for the purpose of illustrating environmental structure only and form no part of the claimed design.

The cable is shown broken away throughout the drawing figures because the specific length of the cable forms no part of the claimed design.
